UNITED STATES PATENT OFFICE.

LAWRENCE E. JOHNSON, OF WINTHROP, AND EDWARD ERICKSON, OF LYNN, MASSACHUSETTS; SAID ERICKSON ASSIGNOR TO VICTOR SHOE MACHINERY COMPANY, OF BOSTON, MASSACHUSETTS, A CORPORATION OF MASSACHUSETTS.

SHOE-HEEL-REDUCING DEVICE.

1,154,572.

Specification of Letters Patent. Patented Sept. 21, 1915.

Application filed March 27, 1915. Serial No. 17,945.

To all whom it may concern:

Be it known that we, LAWRENCE E. JOHNSON, a citizen of the United States of America, and a resident of Winthrop, in the 5 county of Suffolk and State of Massachusetts, and EDWARD ERICKSON, a subject of the King of Sweden, and a resident of Lynn, in the county of Essex and State of Massachusetts, have invented certain new and useful 10 Improvements in Shoe-Heel-Reducing Devices, of which the following is a specification.

This invention relates to devices for removing worn heels from shoes preparatory 15 to applying new heels, and has for its object the provision of a simple and durable device by which a plurality of lifts may be removed from the heel without disturbing the remaining portion thereof.

20 The invention consists of certain novel features of construction and arrangement of parts which will be fully understood by reference to the description of the drawings and to the claims hereinafter given.

25 Of the drawings: Figure 1 represents an elevation of a machine embodying the principles of the present invention. Fig. 2 represents an edge view of the same.

Similar characters designate like parts 30 throughout the figures of the drawing.

In the drawing, 10 is a framework having a base 11 adapted to be secured to a bench or some other means of support. The frame 10 is provided with a projecting portion 12 having openings 13 therethrough. These 35 openings 13 are adapted to receive the projecting portions of a plate 14 made up of Babbitt or some similar soft metal. This plate 14 has its upper face curved to fit the front edge of the heel of a boot or shoe. Pivoted at 15 is a plate 16 having secured to 40 a side face near its outer end, by means of the screws 18, a cutting knife 17. This knife 17 is provided on its rear face with a shou- 45 dered projection 19 adapted to bear against the edge 20 of the plate 16. The cutting edge 21 of the knife 17 is inclined inwardly and midway of its ends is provided with a projection 22 adapted in its downward 50 movement to strike the central portion of the rear end of a heel resting upon the plate 14. The plate 16 is provided with a curved slot 23 in which is positioned a stud 24 secured to the frame 10 and limiting the upward

movement of said plate 16. The plate 16 is 55 also provided with a segment of a gear 25 meshing with a pinion 26 secured to and revolvable with a short shaft 27 mounted in the bearing 28 in the frame 10. The opposite end of the shaft 27 has secured thereto 60 a lever 29 provided with a handle 30 by which the pinion 26 may be revolved. When a worn heel of a shoe is positioned upon the plate 14 and the lever 29 is rotated in the direction of the arrow *a* on Fig. 1 of 65 the drawings, it is obvious that the knife 17 will be forced downwardly upon the heel, and continued movement of the lever 29 will force the knife through the heel removing the required number of lifts therefrom, and 70 in its movement cutting away the nails extending through said heel. Below the supporting plate 14 is mounted a gage 31 having a shank 32 extending through a bearing in the projection 12. A spring 33 surrounds 75 the shank 32 between its bearing and the gage member 31 and forces said gage outwardly or to the left of Fig. 2 of the drawings. The opposite end of the shank 32 has threaded thereto as at 33^x the lever 34 which 80 may be turned by means of the handle 35 to regulate the position of the gage 31.

When the plate 14 becomes unserviceable from continuous use it may be readily removed and a new plate secured to the extension 12. By means of the gage 31 the device may be adjusted so that an equal 85 number of lifts may be removed from each pair of shoes. An inclined wedge-shaped projection 36 is built on the rear face of the 90 member 16 above the cutting edge 21 of the knife 17. This wedge 36 forces the severed lifts away from the remaining portion of the heel on the shoe and prevents too much frictional contact on the knife as it passes 95 through the heel.

This makes a very simple and effective device for preparing shoes for re-heeling in a repair shop. By its use a flat level surface is produced upon the old shoe, thereby 100 making it possible to build up a new heel thereon with very little labor.

It is believed that the operation and many advantages of this invention will be fully apparent from the foregoing description. 105

Having thus described our invention, we claim:

1. In a device of the class described, the

combination of a frame having a forwardly extending work supporting shelf; a member pivoted to the rear of said frame and adapted to be moved toward said support; a knife 5 on the side face of said pivoted member with its cutting edge perpendicular to the pivot of said member; adjustable means at the edge of said work support for positioning the work; and means for moving said member about its pivot and causing said knife 10 to coact with said support.

2. In a device of the class described, the combination of a work support; a pivoted member movable toward said support and 15 provided with a gear segment; a pinion meshing therewith; means for revolving said pinion; and a knife on a side face of said member with its cutting edge below the under side of said member and adapted to 20 coact with the upper face of said work support at some distance from its edge.

3. In a device of the class described, the combination of a work support; a pivoted member movable toward said support and 25 provided with a gear segment; a pinion meshing therewith; means for revolving said pinion; a stop extending through a slot in said member to limit the upward movement thereof; and a knife on a side face of

said member perpendicular to the pivot 30 thereof adapted to coact with the upper face of said work support at some distance from its edge.

4. In a device of the class described, the combination of a work supporting member; 35 a removable plate of soft metal thereon; a cutting knife; a pivoted member supporting said knife with its pivot perpendicular to the cutting edge of said knife; and means for moving said member to bring said knife 40 into coacting relation with said plate.

5. In a device of the class described, the combination of a work supporting member; 45 a removable plate of soft metal thereon; a cutting knife; a pivoted member supporting said knife with its pivot perpendicular to the cutting edge of said knife and having a slot therein; a stop member in said slot; and means for moving said knife into coacting relation with said plate.

Signed by us at Boston, Mass., this 17th day of March, 1915.

LAWRENCE E. JOHNSON.
EDWARD ERICKSON.
